SUPPORTING MEANS FOR PAPER ROLLS

Philip D. Parsons, Swarthmore, Pa., assignor to
 Scott Paper Company, a corporation of Pennsylvania

Application December 5, 1931, Serial No. 579,262

9 Claims. (Cl. 242—53)

My invention relates to means for lifting rolls of paper or other webbing into proper definite position to be engaged by supporting means adapted to permit the paper roll to be rotated by a pulling action upon the web thereof during the withdrawing of the web from the roll.

One of the objects of my invention is to provide manually operated means whereby a heavy roll of paper may be readily lifted and positioned in a machine to which a paper web is to be supplied, the said means having capacity to raise the roll in a vertical direction to any definite height within the range of the apparatus and also horizontally shift the position of the supporting means for the roll in a direction transversely to its axis.

Another object of my invention is to provide means for lifting the paper roll with capacity for adjustment of said means at one or both ends 20 of the roll and longitudinally of the axis thereof and also transversely of said axis whereby the roll may be axially supported and rotated with its ends in definite alinement.

A further object of my invention is to provide 25 means for supporting a roll of paper or other material in a suspended manner with capacity for rotation, associated with means for raising and lowering the roll supporting means.

Another object of my invention is to provide 30 rotatable journals for supporting a roll of paper at an elevation from the floor, associated with lifting platforms arranged beneath the rotatable journals and having means for simultaneously raising and lowering them, the said platforms being spaced apart a distance less than the length 35 of the roll to be lifted whereby a shifting or transportation truck carrying the roll may be moved into position between the platforms so that the ends of the roll are permitted to be 40 positioned above the platforms and lifted from the truck into position for engagement with the rotatable journals.

Referring to the drawings: Fig. 1 is a front view of a roll lifting and supporting means; Fig. 2 is a plan view of the same; Fig. 3 is an end view of the same; Fig. 4 is a vertical section through a portion of the same, taken on line 4—4 of Fig. 2; Fig. 5 is an end view of the friction creating means putting a braking action 50 upon the rotating roll of paper; Fig. 6 is a perspective view of one end of one of the mandrels for supporting the paper roll; Fig. 7 is a side view with part in section of the essential parts of a slitting and perforating machine, as an example of the machine with which my improve- 55

ments may be applied; and Fig. 8 is a perspective view of one of the paper roll plugs axially positioned for receiving the supporting end of the mandrel.

2 and 3 represent two main frames each of which is secured and supported by the floor so that they are at a definite distance apart, each of said frames being provided with a pair of vertical guide rails 4, 4. Sliding upon the said guide rails 4, 4, are carriages 5 having guide 60 rolls 6 engaging said vertical guide rails and are also provided with platforms 7 upon which the ends of the paper roll P may rest, as indicated in Fig. 1. These platforms 7 may furthermore be made slightly depressed or cup-shaped at 7a 70 in Fig. 3. These depressed or cup-shaped portions of the platforms insure the roll of paper taking a definite position upon the said platforms preliminary to it being lifted.

The following means are employed for raising 75 and lowering the carriages 5 together with their platforms 7: At the upper end of the main frame 2 is a transverse shaft 12 carrying upon its ends 2 grooved pulleys 11 adapted to be rotated in unison. To the perimeters of each of the said 80 grooved pulleys are respectively secured the ends of two cables 8, the lower ends of which are severally attached at 9 to opposite sides of the carriage 5 through the mediation of adjustable means 9a, such as a turn-buckle. Secured to the 85 same shaft 12 is a further pulley structure 17 and to the perimeter of this pulley 17 there is secured at 18 the end of a cable 20, said cable 90 extending downward and around an idler pulley 19 arranged near the lower part of the said frame 2. The cable 20 extends horizontally from the idler pulley 19 and is attached to a turn-buckle or adjusting means 21.

Referring now to the other main frame 3, it is provided with a similar arrangement of pulleys 95 and cables for operating the carriage and platform with which it is associated in the following manner. Immediately above the main frame 3 is a transverse shaft 13 suitably journaled and provided at its respective ends with grooved pulleys 11. Connected with each of the said pulleys 11, as indicated at 10, are cables 8 which extend downward and secured to the carriage 5 at 9 where they are provided with turn-buckles 9a. In addition to the grooved pulleys 11, the shaft 100 13 is provided with a pulley 17 corresponding to the similar pulley on the shaft 12 above the main frame 2. Secured at 18 to said pulley 17 is a cable 20 which passes downward and under an idler pulley 19 and thence extends hori- 105 110

zontally to and secured to the turn-buckle 21 aforesaid. The shaft 13 is rotated by a worm and worm wheel gearing 14 which, in turn, is rotated by a spur gearing and pinion mechanism 15, the 5 pinion being manually rotated by a hand wheel 16.

It will now be understood that by rotating the hand wheel 16 in one direction, the carriages 5 and their platforms 7 may be raised and lowered, and it will also be understood that the 10 manually operated means 14, 15 and 16 is caused to operate the lifting means in connection with the main frame 2 because the upper part from said manually operated mechanism is transmitted through the cables 20 to the means for raising and lowering the carriage and turn-buckle associated with said main frame 2. In this manner, both of the carriages 5 are simultaneously raised or lowered, as the case may be.

I will now refer to the means for directly supporting the paper roll and permitting it to rotate, and also for definitely positioning the parts for properly engaging the paper roll and supporting it during its rotation. As similar means is employed in connection with each of the main 20 frames 2 and 3, otherwise than in pointing in opposite directions, the description now to be given will apply to each of the similar devices. The mandrel 22 (Fig. 4) terminates at one end in a journal head 25 and having a collar 26 secured to it, said collar having a transverse flanged portion 26b whereby it engages a part 26a of a plug 50 fitted into the end of the paper roll P, and whereby also the unrolling of the web of the paper roll causes the mandrel 22 to be positively 30 rotated. The journal head 25 may be rigid upon the end of the mandrel 22, but is preferably made adjustable as indicated in Fig. 4, the journal head being positively coupled with the mandrel by a key 28 to cause it to rotate in unison with the mandrel and a screw 27 extends through the journal head into the end of the mandrel for positioning the said journal head longitudinally of the axis of the mandrel to adjust the distance between the parts 26 at opposite sides of the machine to 40 suit the possible differences in lengths of rolls to be handled. The mandrel 22 is journaled in roller bearings at 23 within a cylindrical reciprocable frame 24, said frame 24 being adjustable longitudinally of a box-like frame 37, said frame 50 37 being adjustable horizontally and transversely of the axis of the mandrel 22, the said adjustment being made by manual manipulation of the two screws 38a. The reciprocable frame 24 is guided within the transversely adjustable frame 37 and 55 at the same time being held against rotation therein by being provided with a guide block 29 which is slidable along a longitudinal groove 30 in the frame 37, and this is further assured by a longitudinal rack 31 secured to the reciprocable frame 24 and projecting upwardly into a longitudinal groove 32 on the said frame 37. 33 is a gear secured upon a transverse shaft 34 and caused to rotate with it but permitting slidable motion along said shaft by means of a feather 36 60 between the gear and its shaft, whereby the gear maintains operative connection with the rack 31 at all times, irrespective of the transverse adjustment of the frame 37 and its associated parts including the rack.

70 From the description just given, it will be understood that longitudinal adjustment may be given to the mandrel and frame 24 in which it is journaled by rotating the shaft 34 through the medium of a hand wheel 35 (Figs. 3 and 4). Furthermore, it will be understood that the

mandrel may be adjusted horizontally and transversely of its axis by adjusting the box-like frame 37 within the main frame 3 by means of the manual operable screws 38a.

It will now be understood that with each of the main frames 2 and 3 provided with the adjustable mandrels, the paper roll may be supported by the journal heads 25 of the mandrels and being rotatable through the said mandrels while the webs are being withdrawn. To prevent spinning of the paper rolls upon their mandrels and to prevent looseness in the web while being fed to the machine in which it is to be perforated and slitted or otherwise treated, a drag or friction may be put upon one of the mandrels 22 and this may be accomplished as indicated in Figs. 4 and 5. Referring to Fig. 4, it will be seen that the left hand end of the mandrel 22 has keyed to it a friction drum 39 and that about this drum is a brake band comprised of the following parts. A stationary section 40 is pivoted at 44 upon a stationary bracket 45 and the under curved surface of said part 40 is provided with a friction band section 49. A spring 42 presses the said portion 40 downward toward the friction drum and the tension of the spring may be adjusted by a screw 43. Curved sections 41 are respectively hinged to the ends of the section 40, as indicated at 41a, and these curved sections 41 are also provided with brake linings 48 pressing in direct contact with the friction drum. A spring and bolt mechanism 47a-48a is employed to draw the free ends of the braking sections 41 toward each other in more or less tight relation with the brake drum 39 and the tension of the spring may be manually adjusted by the nut 47. As seen, the bolt 48 extends through flanges on the parts 41 and through a lower bracket 46 extending from the reciprocable frame 24. As the mandrels are rotated under the pull of the paper web, the drum 39 at the end of one of the mandrels will be rotated, and this action of being rotated will be more or less resisted by the braking action of the brake band upon the friction drum. This will put a tension on the roll of paper to prevent spinning and the amount of this tension upon the paper web may be adjusted as above described.

In the operation of the device, the amount of lift which is necessary to the carriages 5 and the platforms 7 to bring the axis of the paper roll into alignment with the journal heads 25 of the mandrels will depend upon the diameter of the paper rolls and, in the illustration in Fig. 1, it is seen that a very large roll has been placed upon the journal heads of the mandrels and that the total lift of the paper roll from the truck T with which it was brought into position upon the platform 7 is relatively very small. The carriages 5 and their platforms 7 are raised just sufficient to support the paper roll axially of the mandrels. If, on the other hand, the paper roll was relatively half of the diameter shown in Fig. 1, the amount of lift by the carriages 5 and their platforms 7 would be very much greater than the lift required with a roll of the diameter illustrated. The lift may, of course, be to any extent desired or needed to secure the proper elevation of the paper roll to bring it axially into alignment with the mandrels. If, for any reason, the support of the paper roll in its elevated position was such that the mandrels did not enter the plugs of the roll, the screws 38a may be adjusted to horizontally 150

adjust one or both of the mandrels and this same adjustment may be resorted to should the paper web have any tendency to diagonal movement in being unwound.

5 It will also be noted that in adjusting the paper roll upon the heads of the mandrels, the mandrels are first withdrawn by rotating the hand wheels 35 and when said mandrel heads are within the casings 2 and 3, the carriages 5 and 10 platforms 7 are lifted to the proper height and thereupon the hand wheels 35 are rotated in opposite directions for causing the mandrel heads to be projected and to enter the apertures 26a in the plugs 50 of the paper rolls. Thereupon 15 the carriages 5 and their platforms 7 are caused to be lowered, leaving the paper rolls to remain suspended upon the mandrels.

It will now be apparent that I have devised a novel and useful construction of apparatus which 20 embodies the features of advantage enumerated as desirable, and while I have in the present instance shown and described the preferred embodiment thereof which has been found in practice to give satisfactory and reliable results, it 25 is to be understood that I do not restrict myself to the details stated as the same are susceptible of modification in various particulars, without departing from the spirit or scope of the invention.

30 Having thus described my invention, what I claim and desire to secure by Letters Patent is:

1. In a device of the character described, the combination of two lifting devices spaced at a distance apart with common means for simultaneously operating the lifting devices in a vertical direction, a journal head arranged above each of the lifting devices, and means for reciprocating the journal heads relatively toward and from each other, whereby said heads may be 35 adjusted further apart during the upward operation of the lifting devices and thereafter adjusted relatively closer together for supporting the roll upon the journal heads, and wherein further, the lifting devices comprise vertical 40 guides, carriage portions having vertical reciprocation upon said guides and provided with horizontally extending platforms, and wherein also cables and pulleys are provided for simultaneously operating the carriages and their platforms 45 in a vertical direction.

50 2. In a device of the character described, the combination of two lifting devices spaced at a distance apart with common means for simultaneously operating the lifting devices in a vertical direction, a journal head arranged above each of the lifting devices, and means for reciprocating the journal heads relatively toward and from each other, whereby said heads may be 55 adjusted further apart during the upward operation of the lifting devices and thereafter adjusted relatively closer together for supporting the roll upon the journal heads, and wherein further, the lifting devices comprise two vertically 60 movable carriages provided with platforms, a rockshaft over each of the carriages, lifting cable devices from each carriage to its rockshaft, and a common cable power transmission means for

simultaneously operating the rockshafts for raising and lowering the carriages.

3. In a device of the character described, the combination of two lifting devices spaced at a distance apart with common means for simultaneously operating the lifting devices in a vertical direction, a journal head arranged above each of the lifting devices, and means for reciprocating the journal heads relatively toward and from each other, whereby said heads may be 80 adjusted further apart during the upward operation of the lifting devices and thereafter adjusted relatively closer together for supporting the roll upon the journal heads, and wherein further, the lifting devices comprise two oppositely directed and spaced platforms having means for simultaneously raising and lowering said platforms.

4. In a device of the character described, the combination of two lifting devices spaced at a distance apart with means for simultaneously operating the lifting devices for raising and lowering a roll of paper, means relatively positioned with respect to the lifting devices for sustaining the weight of the roll of paper when lifted and 100 permitting its rotation upon a horizontal axis, and a supporting truck for supporting and moving a roll of paper into position upon the lifting devices, said truck being of a length to move freely in the space intermediate of the lifting 105 devices.

5. The invention according to claim 4, wherein further, the lifting devices include a cable connection arranged at the rear of the space between the lifting devices occupied by the truck. 110

6. The invention according to claim 4, wherein further, the lifting devices comprise two independently arranged vertically movable carriages, a common cable hand operated and extending to each of the lifting carriages, and means for 115 adjusting the length of the cables.

7. In a machine of the character described, the combination of two lifting devices, means for simultaneously operating the lifting devices in a vertical direction, journal heads arranged above 120 each of the lifting devices and respectively having a shaft supported in widely spaced roller bearings, and means for adjusting the shafts and their journal heads in a horizontal transverse direction relatively to the lifting devices, whereby 125 the axial position of the journal heads may be adjusted forward or backward to engage the two ends of a roll of paper while in the custody of the lifting devices.

8. The invention according to claim 7, wherein 130 further, the shafts of the journal heads are supported upon roller bearings and said bearings are arranged in transversely movable frames supported upon pedestals, and combined with manually adjustable means in connection with the 135 supporting devices at each end of the machine for adjusting the transversely movable frames and their roller bearings.

9. The invention according to claim 7, wherein further one of the journal heads has a plug 140 engaging the paper roll so as to be rotated by it.

PHILIP D. PARSONS.
